STOKER APPARATUS

Donald J. Moss hart, Springfield, Pa., assignor to Westinghouse Electric & Manufacturing Company, East Pittsburgh, Pa., a corporation of Pennsylvania

Application November 7, 1939, Serial No. 303,197

4 Claims. (Cl. 122—4)

My invention relates to inclined stokers incorporating a multiple retort underfeed section followed by an overfeed section having moving grate elements for agitating the fuel bed passing thereover and it has for an object to provide a rear water wall which extends upwardly and over the overfeed section in suitable, spaced relation with respect to the latter so as to improve combustion and to avoid stratification of gases passing upwardly in the furnace chamber from the fuel bed.

With stokers of the underfeed type, the overall effective length may be increased by the provision of an overfeed section of suitable length; and, in order that the fuel bed may be effectively handled by the overfeed section, it is desirable that the latter shall incorporate movable grate elements which agitate the fuel bed to break up fused masses and to secure more thorough permeation of the bed by air. There is a tendency for the gaseous media issuing from the overfeed section to pass upwardly in a stratified condition, that is, adjacent portions of the upwardly moving gases may have a wide variation in the ratio of combustible to air, some portions being over-rich in combustible and some having excess air; and, in extreme cases, stratification may result in such incomplete combustion that smoke in substantial quantities is discharged. The irregularity in gaseous media issuing from the overfeed section will be apparent when one considers what occurs when a fused mass is fractured due to agitation. Immediately, there ensues vigorous emission of volatile matter and the local air supply may be inadequate to promote complete combustion immediately above the fuel bed. On the other hand, the reverse situation may occur with respect to an adjacent region on the overfeed section, this being particularly true as the rear end of the overfeed section is approached. Accordingly, therefore, I provide a water wall forming the back wall of the furnace chamber and which extends upwardly at the rear of the discharge end of the overfeed section and which then extends upwardly and forwardly in suitable spaced relation with respect to the overfeed section so as to provide a wall substantially covering or overlapping the overfeed section, such wall promoting turbulence and more thorough mixture of gases issuing from the overfeed section with the result that more complete combustion is thereby secured. Aside from the wall promoting turbulence to secure more complete combustion of the gaseous media, it also serves to deflect particles of fuel or ash from the gas stream

and backwardly onto the fuel bed to reduce the quantity of such particles that may be carried along with the gases through the gas passages of a boiler installation, whereby the amount of such particles deposited on the baffles, the tubes, and possibly carried out through the stack, may be substantially reduced. A further object of my invention is, therefore, to provide combustion apparatus having these advantageous features of construction and operation.

A further object of my invention is to provide an inclined multiple retort stoker having an overfeed section including movable grate elements together with a rear water wall which overlaps the overfeed section and in suitable spaced relation with respect to the latter to promote turbulence of gaseous media issuing from the fuel bed on the overfeed section together with means for admitting secondary air through the water wall at the upper end of the portion which overlaps the overfeed section.

A further object of my invention is to provide for an inclined stoker, including a multiple retort underfeed section, an overfeed section including movable grate elements for agitating the fuel bed passing thereover and a horizontal orifice normally filled with ash and refuse to seal the furnace chamber and through which ash and refuse is continuously discharged due to the pushing effect of the moving elements of the overfeed section, a water wall which forms the top wall of the orifice and which extends upwardly and forwardly toward the front wall of the furnace chamber and in suitably spaced relation with respect to the overfeed section so as to cover the latter in order to promote more thorough turbulence and a mixture of the gaseous media issuing from the fuel bed, to minimize stratification and smoke and to promote a longer path of gas travel through the furnace chamber in order to effect more complete combustion.

These and other objects are effected by my invention as will be apparent from the following description and claims taken in connection with the accompanying drawings, forming a part of this application, in which:

Fig. 1 is a vertical sectional view showing my improved water wall construction in relation to the stoker and to the furnace chamber and boiler; and

Fig. 2 is a view similar to Fig. 1, but showing a continuous ash discharge type of stoker.

Referring now to the drawings more in detail, an inclined stoker, at 10, forms the bottom wall of the furnace chamber 11, the stoker being of

a well-known type and including a multiple retort underfeed section 12 followed by an overfeed section 13, the overfeed section comprising a multiplicity of moving grate elements indicated generally at 14 and which serve to agitate the fuel bed passing over the overfeed section and to promote the travel thereof in the direction of fuel feed.

A water wall 15 including upwardly-extending parallel tubes 16 extends upwardly at the rear of the discharge end of the overfeed section and then forwardly and upwardly so as to overlap the latter, thereby providing a turbulence space or chamber between the fuel bed on the overfeed section and such overlapping portion of the water wall to promote more thorough mixture or turbulence of gaseous media issuing from the fuel bed, the turbulence chamber or space so provided insuring a more thorough mixture of the gases and better combustion thereof with minimized stratification and smoking on that account.

In Fig. 1, the invention is shown as applied to a stoker having an ash pit 17 from which ash and refuse are discharged by means of the clinker grinder 18, the accumulations of ash and refuse in the pit 17 above the clinker grinder serving in the usual way to seal the furnace chamber 11 against the ingress of air. In this embodiment, the water wall includes: the lower header 20 from which the first vertical section, at 21, extends upwardly to a rear wall portion common both to the ash pit 17 and to the furnace chamber 11; a second section, at 22, continuous with the first section, at 21, and which extends upwardly and forwardly toward the front wall 23 of the furnace chamber so as to cover or overlap the vertical projection of the ash pit 17; a third section, at 24, continuous with the second section and which extends upwardly and forwardly toward the front wall 23 but with a greater degree of horizontal component of direction than the second section; and a fourth section, at 25, continuous with the third section and which extends upwardly, the junction of the sections 24 and 25 providing an angular or re-entrant portion 26, which, with the furnace front wall 23, forms an orifice area in the furnace chamber above the stoker.

An air chamber 27 is arranged transversely and rearwardly of the junction portion 26 so that spaces between tubes at the junction portion may provide openings for issuance of air from the chamber 27 into the furnace chamber 11. Air is supplied to the chamber 27 by a conduit 28, in turn, supplied by any suitable means. As shown in Fig. 1, air is supplied to the conduit 28 from the conduit 29 connecting the air preheater 30 with the plenum chamber 31 of the stoker, the conduits having dampers 32 and 33 to secure appropriate division of the air.

Aside from the feature of having the water wall overlap the overfeed section to promote turbulence of gases and more thorough combustion, the admission of secondary air at the junction portion 26 further aids in promoting turbulence and more effective and complete combustion, particularly as such air is admitted generally in a horizontal direction and transversely of the throat or orifice of the gaseous flow passage of the furnace and boiler chamber. Furthermore, the overlapping water wall feature and the secondary air admission assists in the settlement of particles, carried from the overfeed section by the gas stream, back onto the underfeed section and promotes, for a given furnace chamber vol-

ume, a relatively long path of gas travel, the length being increased because of the sinuous nature given thereto by the overlapping wall feature and by the energy of the entering secondary air. Furthermore, by having the secondary air admitted through the junction portion 26, it is assured that, not only shall the effect thereof be uniform throughout the width of the stoker, but it is admitted to a region having a minimum distance with respect to the horizontal dimensions of the furnace chamber, with the result that most effective penetration of the gas stream by the transverse stream of entering secondary air is secured.

Fig. 2 shows an embodiment of my invention for use with a continuous ash discharge type of stoker. With this type, instead of having an ash pit normally having ash maintained therein by the clinker grinder to effect an air seal and from which ash is intermittently discharged by operation of the clinker grinder, such a pit and clinker grinder are omitted, ash being discharged through a horizontal orifice, at 35, defined by the ash plate 36 and the upper wall 37, the orifice, at 35, being normally filled with ash and refuse to secure the desired sealing of the furnace chamber against the infiltration of air. The orifice is so designed, and the ash plate 36 is so adjusted with respect to the reciprocating movement of the last grate member 14 of the overfeed section that the pushing effect imparted by such last grate member serves to feed ash and refuse continuously through the orifice without undue accumulation thereof in front of the orifice. In this embodiment, the water wall 16a has a different form, it being comprised by the following sections: a first horizontal section, at 38, whose end is connected to the header 39 and which forms the upper wall of the orifice 35; a second upright or vertical section, at 40, continuous with the section, at 38, and which extends upwardly; a third section, at 41, continuous with the second section and which extends upwardly and forwardly toward the front wall 23a of the furnace chamber so as to overlap the overfeed section 13a; and a fourth section, at 42, continuous with the third section and which extends upwardly and preferably also rearwardly. The vertical extent of the second section, at 40, is determined by the desired spacing of the upwardly and forwardly inclined section, at 41, with respect to the overfeed section 13a, this space being so chosen as to secure effective turbulence and mixture of the gases issuing from the overfeed section.

In both embodiments described, not only does the section of the water wall overlapping the overfeed section promote better turbulence in a mixture of the gases issuing from the overfeed section, but the directive effect of such wall causes the stream of such gases to be projected forwardly toward the front wall of the furnace chamber with the result that such gases are caused to mix thoroughly with gases issuing from the underfeed section, whereby more thorough mixture of all of the gases and combustion may be secured. Also, as already pointed out, this forward directive effect promotes deposition of ash and particles back onto the underfeed section and gives a longer path of gas travel and, therefore, an increased time element for a given gas velocity to promote more complete combustion.

While I have shown my invention in several forms, it will be obvious to those skilled in the art that it is not so limited, but is susceptible of various other changes and modifications without

departing from the spirit thereof, and I desire, therefore, that only such limitations shall be placed thereupon as are specifically set forth in the appended claims.

What I claim is:

1. The combination with a stoker forming the bottom of a furnace chamber and including a multiple retort underfeed section followed, in the direction of fuel feed, by an overfeed section including a plurality of pivotally-connected links providing for undulatory movement, agitation, breaking open and crumbling of the fuel bed passing thereover: of a water wall forming the back wall of the furnace chamber and including upwardly-extending water tubes, said water wall including a first section extending upwardly at the rear of the discharge end of the overfeed section and a second section continuous with the first section and which extends upwardly and forwardly toward the furnace chamber front wall and in spaced relation with respect to the overfeed section so as to cover substantially the latter.

2. The combination with a stoker forming the bottom of a furnace chamber and including a multiple retort underfeed section followed, in the direction of fuel feed, by an overfeed section including a plurality of pivotally-connected links providing for undulatory movement, agitation, breaking open and crumbling of the fuel bed passing thereover: of a water wall forming the back wall of the furnace chamber and including upwardly-extending parallel tubes; said water wall including a first section extending upwardly at the rear of the discharge end of the overfeed section, a second section continuous with the first section and extending upwardly and forwardly toward the front wall of the furnace chamber and in spaced parallel relation with respect to the overfeed section so as to cover substantially the latter, and a third section continuous with the first section and which extends upwardly.

3. The combination with a stoker forming the

bottom of a furnace chamber and means including spaced upper and lower walls defining an ash discharge orifice which is normally filled with ash to form an air seal and through which ash is continuously discharged, said stoker comprising a

5 multiple retort underfeed section followed, in the direction of fuel feed, by an overfeed section including moving grate elements for agitating the fuel bed and for imparting a pushing effect to ash 10 passing through the orifice: of a water wall forming the back wall of the furnace chamber and including upwardly-extending parallel water tubes; said water wall including a first horizontal section forming the upper wall of said orifice, a second 15 section continuous with the first section and extending upwardly, a third section continuous with the second section and extending upwardly and forwardly toward the furnace chamber front wall and in spaced substantially parallel relation to the 20 overfeed section so as to overlap substantially the overfeed section, and a fourth section continuous with the third section and which extends upwardly.

4. The combination of a stoker forming the 25 bottom of a furnace chamber and including a multiple retort underfeed section followed, in the direction of fuel feed, by an overfeed section including a plurality of pivotally connected links providing for undulatory movement, agitation, 30 breaking open and crumbling of the fuel bed passing thereover; of a water wall forming the back wall of the furnace chamber, said water wall including a section which extends upwardly and forwardly from the rear of the discharge end of 35 the stoker toward the front of the furnace in spaced relation to and overlying a major portion of the stoker overfeed section, whereby hot gases rising from said overfeed section are directed forwardly to mix with the gases rising from the 40 underfeed section.

DONALD J. MOSSHART.
